US00D631781S

(12) **United States Design Patent**
Mogren

(10) **Patent No.:** **US D631,781 S**
(45) **Date of Patent:** **** Feb. 1, 2011**

(54) **JEWELRY**

(76) Inventor: **Scott Mogren**, 2115 Lydia Ave.,
Maplewood, MN (US) 55109

(**) Term: **14 Years**

(21) Appl. No.: **29/362,330**

(22) Filed: **May 24, 2010**

(51) **LOC (9) Cl.** **11-03**

(52) **U.S. Cl.** **D11/96**

(58) **Field of Classification Search** **D11/95, D11/96, 97, 98, 99, 116, 184, 1, 86, 40, 79, D11/82, 162, 157, 103, 222, 66, 104, 107, D11/13, 133, 172, 25, 41, 43, 58, 11; 63/1.11, 63/1.12, 1.13, 1.14, 1.16, 1.18, 13, 14.1, 63/35, 39**

See application file for complete search history.

(57) **CLAIM**

The ornamental design for jewelry, as shown and described.

DESCRIPTION

FIG. 1 is a front view of the invention;

FIG. 2 is a back view of the invention;

FIG. 3 is a top view of the invention;

FIG. 4 is a bottom view of the invention;

FIG. 5 is a left side view of the invention;

FIG. 6 is a right side view of the invention;

FIG. 7 is an unassembled front view of the invention;

FIG. 8 is an unassembled side view of the bottom portion the invention;

FIG. 9 is an unassembled side view of the bottom portion of a coupling member of the invention;

FIG. 10 is an unassembled back view of a coupling member of the invention;

FIG. 11 is an unassembled front view of a coupling member of the invention; and,

FIG. 12 is an unassembled top view of a coupling member of the invention.

The broken line showing of the two circles in FIG. 7, illustrates environmental structure and forms no part of the claimed design.
